UNITED STATES PATENT OFFICE.

ROBERT W. POCOCK AND AUGUSTINE J. POCOCK, OF DAYTON, OHIO.

VALVE AND METHOD OF SEALING SAME.

1,292,962.

Specification of Letters Patent.

Patented Jan. 28, 1919.

Application filed September 25, 1917. Serial No. 193,100.

To all whom it may concern:

Be it known that we, ROBERT W. Pocock and AUGUSTINE J. Pocock, citizens of the United States, residing at Dayton, in the county of Montgomery and State of Ohio, have invented certain new and useful Improvements in Valves and Methods of Sealing Same, of which the following is a specification.

10 This invention relates to a new and useful method of sealing the valves against leakage and protecting the sealing medium from loss or displacement during shipment of the pumps and until they have been installed in use. The object of the invention is the producing of a valve which is more certainly secure against leakage than are valves as now commonly constructed, referring more particularly to automatic or puppet valves 20 for controlling the passage of liquids more than ordinarily hard to hold, such as gasoline, alcohol, etc. A further object of the invention is to provide means for protecting the sealing medium from displacement or 25 loss during the shipment of pumps containing the valves. This latter specified means includes a method of inclosing the valve-sealing medium with a soluble substance until the valve is put into use, after which the 30 soluble material disappears and renders the sealing medium effective for the use intended. The accompanying drawings are made up after the manner in which a foot valve might be constructed for use on the lower end of a suction pipe, this however, being only one of the forms which its construction might take and at the same time include the essential features of the improvements. For example, the drawings show a 40 wing valve that is guided in the bore of the seat, this being one form of guiding the valve. So far as the present invention is concerned the manner of guiding the valve is of small importance as is also the form 45 the valve may take. It may be guided from the top and instead of being round as shown it might take some other form.

50 Referring more particularly to the accompanying drawings, Figure 1 is a vertical sectional view of the valve as a whole, a portion of the strainer as well as the suction pipe being broken away. Fig. 2 is a similar section including the strainer, and Fig. 3 is a sectional view on the line 3-3 of 55 Fig. 1.

In a detail description of the invention similar reference characters indicate corresponding parts in the drawings.

The body 1 of the valve may vary somewhat in design or form from that shown in the drawings provided it retains the annular pocket 20 surrounding the stationary member of the valve structure which provides a seat. In the accompanying drawings this part is shown as a vertical wall 2 around the passage 3 and the upper end of which provides the valve seat 5. The wall 2 is united to a surrounding horizontal portion 4 which joins the bottom of the casing 1 and forms the bottom of pocket 20. The wall 2, 60 as before stated, surrounds the passage 3 and extends vertically above and below the bottom 4, and as before stated the upper end of said wall 2 provides a seat for the valve 6. The valve 6 is provided with a 65 downwardly projected skirt of cylindrical portion 7 which incloses the wall 2 when the valve is on its seat as in Fig. 1. Between said skirt 7 and the wall 2 there is an annular space 8 which indicates a clearance 70 when the valve is seated. The valve 6 is of a well known wing form, the same being provided with downwardly projected web portions 8 which form guides 9 that engage and slide against the inner surface of the 75 wall 2 in the operations of the valve. The portion of the wall 2 which extends above the horizontal wall 4 provides the pocket 20 before referred to. The pocket 20 is designed to contain an element for sealing the 80 valve when closed to prevent leakage. This sealing medium or element consists of a metallic fluid 10, such as mercury. The high specific gravity of mercury causes it to remain in the pocket 20 surrounding the 85 valve seat regardless of the flow of lighter liquids over it when the valve is lifted and in operation. It at the same time prevents impurities of any kind entering or accumulating in the pocket inasmuch as the specific 90 gravity thereof is much higher than that of most materials which might form the impurities referred to. Referring to Fig. 1 of the drawings, the valve 6 is there shown to be seated with the skirt portion 7 thereof 95 submerged in the mercury. It is impossible for the liquid being pumped to get to the seat of the valve, that is, the point 5 where the valve rests without first driving the metallic fluid or mercury through the seat. 100 105 110

This element being of such character that it will not pass through small openings readily, the consequence is that it acts as an effectual stop to the liquid being pumped, returning 5 through the valve when it is closed. The top or the mercury chamber is partly inclosed by a flange 19 that projects from the inner side of the valve casing, there being a sufficient opening 21 for the skirt of the 10 valve to pass through in rising and seating.

Referring more especially to a valve as used in dispensing pumps or to the foot valve attached to the suction line of such pumps, it will be noted that we provide 15 against accident in shipment, and also against the injury of a valve seat by foreign substances, such as sand, scale or such material being caught on the seat as the valve descends. This often occurs from these substances being left in the pipes, castings or 20 tank, or possibly getting in during shipment. These impurities when the pump has been in action a short time, will be passed on and there is very little danger of damage 25 from this source after the pump has been in use a short time. To guard against this and at the same time to keep the fluid metal in its place during shipment, we provide a seal over the top of the mercury, which holds the same 30 in place and at the same time supports the valve from its seat, as shown in Fig. 2, until the pump is put in use. This substance consists of a body of wax or paraffin 11 or any material that is soluble under the action of 35 gasoline, or passing liquid. This soluble substance is placed while soft on top of the mercury practically to the height of the valve seat and partially under the inwardly extending rib 19. This completely incases 40 the mercury, and the soluble material itself for the time being forms the valve seat by means of the surrounding skirt of the valve resting on it, and being free to lift and close under the action of the pump, operating to 45 all intents and purposes as the valve does

while it is coming in contact with the mercury. At the same time, this seat receives all the dirt during the preliminary pumping and allows it to pass on. This soluble material, however, wears away during the 50 cleaning process and in a short time breaks through into the mercury and operates as above described. The valve casing 1 terminates at its upper end in an internally screw-threaded portion 12 which receives a nipple 13, which is provided with a series of 55 projections 14 that form abutments with which the top of the valve engages when moving from its seat under the suction created. 15 is a suction pipe connected with the 60 nipple 13 and forming the outlet from the valve. The lower portion of the valve casing is provided with a frame 16 inclosed by a bottom 17 and surrounded by a wire screen 18 through which the gasoline is strained in 65 passing into and through the valve.

It will be readily apparent that the structural details may be more or less varied from those shown and referred to in the foregoing description without departing from the 70 principles of the invention as embodied in the statement of the scope thereof, and as set forth in the claim.

Having described our invention, we claim: 75
A method of sealing a valve of liquid dispensing pumps and protecting the valve or seat from damage in transit and in the initial operation thereof, which consists in placing a sealing fluid of a higher specific gravity than that of the liquid passing 80 through the valve, around the valve seat, and in placing over the exposed surface of said fluid a body of soluble matter which is dissolved by the liquid passing through the valve in its initial operation whereby the 85 sealing fluid becomes exposed.

In testimony whereof we affix our signatures.

ROBERT W. POCOCK.

AUGUSTINE J. POCOCK.
